(12) **United States Design Patent** (10) **Patent No.:** **US D924,914 S**
Hayamizu (45) **Date of Patent:** **** Jul. 13, 2021**

(54) **DISPLAY SCREEN WITH TRANSITIONAL
GRAPHICAL USER INTERFACE**

(71) Applicant: **HOYA CORPORATION**, Tokyo (JP)

(72) Inventor: **Eiji Hayamizu**, Tokyo (JP)

(73) Assignee: **HOYA CORPORATION**, Tokyo (JP)

(**) Term: **15 Years**

(21) Appl. No.: **29/710,112**

(22) Filed: **Oct. 21, 2019**

(30) **Foreign Application Priority Data**

May 16, 2019 (JP) 2019-010594

(51) **LOC (13) Cl.** **14-04**

(52) **U.S. Cl.**
